UNITED STATES PATENT OFFICE.

FRANK CIAO AND PHILIP MARGURIET, OF WILMERDING, PENNSYLVANIA.

DESIGN FOR A COFFER.

Application filed April 29, 1925. Serial No. 13,250. Term of patent 14 years.

To all whom it may concern:

Be it known that we, FRANK CIAO and PHILIP MARGURIET, citizens of the United States, residing at Wilmerding, in the county of Allegheny and State of Pennsylvania, have invented a new, original, and ornamental Design for a Coffe, of which the following is a specification, reference being had to the accompanying drawings, forming part hereof.

The drawings show the coffer, the subject matter of the present invention.

In the drawings Figure 1 is an isometric view of the coffer showing two sides there-

What we claim is:

The ornamental design for a coffer, substantially as shown.

In testimony whereof, we hereunto set our hands.

FRANK CIAO.
PHILIP MARGURIET.
